Assistant Examiner — Richard E Yenchesky

(57) **CLAIM**

The ornamental design for a vacuum cleaner storage rack as shown and described.

DESCRIPTION

1. Vacuum cleaner storage rack
  - 1.1 Back
  - 1.2 Front
  - 1.3 Right Side
  - 1.4 Left Side
  - 1.5 Perspective
  - 1.6 Top
- 1, Name of this design product: Vacuum cleaner storage rack; 2, Purpose of this design product: Storage vacuum cleaner; 3, The design key points of this design product: shape; 4, Pictures or photos that can best show the design points: Stereogram; 5, The bottom surface of this design product is an area that is not easily visible or invisible during use, and the bottom view is omitted.

1 Claim, 6 Drawing Sheets
